UNITED STATES PATENT OFFICE

92,459

DESIGN FOR A GAME SCORING DEVICE

Willard H. Francis, Los Angeles, Calif., assignor to George L. Strehlke, Los Angeles, Calif.

Application April 2, 1934, Serial No. 51,285

Term of patent 7 years

To all whom it may concern:

Be it known that I, WILLARD H. FRANCIS, a citizen of the United States, residing at Los Angeles, in the county of Los Angeles and State of California, have invented a new, original, and ornamental Design for a Game Scoring Device, of which the following is a specification, reference being had to the accompanying drawing forming a part thereof.

The figure is a perspective view of the game scoring device, showing my new design.

I claim:

The ornamental design for a game scoring device, as shown.

WILLARD H. FRANCIS.
